J. E. SEDLACEK,
DRAFT EQUALIZER,
APPLICATION FILED SEPT. 17, 1917.

1,274,089.

Patented July 30, 1918.

Attorney

UNITED STATES PATENT OFFICE.

JOHN E. SEDLACEK, OF HOWELLS, NEBRASKA.

DRAFT-EQUALIZER.

1,274,089.

Specification of Letters Patent. Patented July 30, 1918.

Application filed September 17, 1917. Serial No. 191,823.

To all whom it may concern:

Be it known that I, JOHN E. SEDLACEK, a citizen of the United States, residing at Howells, in the county of Colfax and State 5 of Nebraska, have invented certain new and useful Improvements in Draft-Equalizers, of which the following is a specification, reference being had to the accompanying drawings.

10 This invention relates to certain improvements in draft equalizers and has relation more particularly to a device of this general character especially designed and adapted for use in connection with binders or the like and it is an object of the invention to provide a device of this general character having novel and improved means whereby a direct pull is imposed upon the vehicle.

It is also an object of the invention to provide a novel and improved device of this general character whereby the animals are relieved from the major portion of the weight of the draft equalizer.

The invention also has for an object to 25 provide a novel and improved device of this general character wherein an equalizing element is pivotally engaged with the truck pole of the vehicle and wherein the trees are directly engaged with the opposite end 30 portions of the draft element.

The invention consists in the details of construction and in the combination and arrangement of the several parts of my improved draft equalizer wherein certain important advantages are attained and the device rendered simpler, less expensive and otherwise more convenient and advantageous for use, as will be hereinafter more fully set forth.

40 The novel features of my invention will hereinafter be definitely claimed.

In order that my invention may be the better understood I will now proceed to describe the same with reference to the accompanying drawings wherein:

Figure 1 is a view in top plan of a draft equalizer constructed in accordance with an embodiment of my invention, the co-acting truck pole being shown in fragment; and

50 Fig. 2 is a fragmentary view partly in rear elevation and partly in section of the equalizer as herein embodied, certain of the parts being omitted for clarity in disclosure.

55 As disclosed in the accompanying drawings P denotes the truck pole as generally

employed in connection with binders or the like and co-acting with the outer end portion of the truck pole is the tongue truck T of a conventional type. The upstanding post 1 of the truck T extends above the outer end portion of the truck pole to afford a pivotal mounting for the laterally directed beam or extension 2 of a predetermined length. Also mounted upon the upper portion of the post 1 and above the beam or extension 2 is a guide pulley 3 for a purpose to be hereinafter more particularly referred to. The opposite or outer end portion of the beam or extension 2 is also provided above its upper face with the guide pulley 4 to be hereinafter more particularly referred to. The post 1 is also provided intermediate its length with an outstanding annular flange 1^a or the like upon which the pole P rests and which also serves to limit upward movement of the post 1 through said pole P. Operatively engaged with the beam or extension 2 at a predetermined point inwardly of its outer end is a caster 80 wheel 5 or the like for supporting said beam or extension in order to relieve the draft animals of the weight thereof.

M denotes an equalizing member comprising two angularly related arms 6 and 7 of uneven length and preferably in a ratio of three to 2, said arms at their junction are pivotally engaged as indicated at 8 with the truck pole P at a predetermined point inwardly of the outer end thereof.

The longer arm 6 of the member M extends in a direction opposite to the beam or extension 2 and secured to the outer end portion of said arm 6 is a flexible member 9 which extends inwardly of the truck pole P and beyond the outer or forward end thereof. Said flexible member 9 is also operatively engaged with the guide pulley 3. The outer end portion of the flexible member 9 is suitably secured to a double tree 10 at 100 substantially the longitudinal center thereof and operatively engaged with the opposite end portions of the double tree 10 are the swingle trees 11.

The shorter arm 7 is disposed in a direction substantially rearwardly of the truck pole P and operatively engaged with the free end portion thereof is the flexible member 12 which is disposed around the guide pulley 4 arranged adjacent the outer or free 110 end of the extension or beam 2. The flexible member 12 extends a predetermined distance

in advance of the beam or extension 2 and is secured to the elongated tree 14 at substantially the longitudinal center thereof. Pivotally engaged with the opposite end 5 portions of the tree 14 are the trees 15. The pivotal mounting 16 of each of the trees 15 is such as to afford an outwardly disposed short arm *a* and an inwardly directed long arm *b*. To the outer end portion of each of 10 the smaller arms *a* is operatively engaged a swingle tree 17. The inner or adjacent ends of the longer arms *b* of the trees 15 are connected by a clevis 17 or the like and secured to said clevis is a swingle tree 18.

15 To one skilled in the art it will be self evident that a draft equalizer constructed in accordance with an embodiment of my invention assures a direct pull of the draft animals and also permits the draft animals 20 to be so hitched to a binder or the like as to prevent the animals from traveling through the standing grain and which is of particular import. It will also be noted that the beam or extension 2 is capable of swinging 25 or pivotal movement relative to the truck pole P. This in practice has materially increased the efficiency of the equalizer.

From the foregoing description, it is thought to be obvious that a draft equalizer 30 constructed in accordance with my invention is particularly well adapted for use by reason of the convenience and facility with which it may be assembled and operated and it will also be obvious that my invention is 35 susceptible of some change and modification without materially departing from the prin-

ciple and spirit thereof, and for this reason I do not wish to be understood as limiting myself to the precise arrangement and formation of the several parts herein shown 45 in carrying out my invention in practice except as hereinafter claimed.

I claim:

In combination with a draft pole of a vehicle, a beam having an end portion overlying the pole and extending laterally therefrom, a truck, an upstanding member carried by the truck and disposed through the draft pole and the beam for pivotal connection with said pole and beam, said upstanding members being provided with an annular flange upon which the pole rests, a member comprising a pair of angularly related arms pivotally engaged with the pole at a point inwardly of the beam, a pulley rotatably supported by the upstanding member of the truck at a point above the beam, a guide member carried by the outer end portion of the beam, flexible members secured to the free ends of the arms of the first named member, one of said members coacting with the pulley and the second of said flexible members with the guide member carried by the beam, and trees to which the forward end portions of the flexible members are connected.

In testimony whereof I hereunto affix my signature in the presence of two witnesses.

JOHN E. SEDLACEK.

Witnesses:

WALTER B. SADILEK,
THOMAS ALLEN.
